[57] CLAIM

The ornamental design for a solar powered temperature monitor, as shown.

DESCRIPTION

FIG. 1 is a top, front and left side perspective view of a solar powered temperature monitor showing my new design;

FIG. 2 is a left side elevational view;

FIG. 3 is a top plan view;

FIG. 4 is a bottom plan view;

FIG. 5 is a right side elevational view;

FIG. 6 is a front elevational view; and,

FIG. 7 is a rear elevational view thereof.

FIG. 1 has been drawn on an enlarged scale with respect to FIGS. 2-7.

FIG. 2

FIG. 3

FIG. 4

FIG. 5

FIG. 6

FIG. 7
